Primary Examiner — Wendy L Arminio*Assistant Examiner* — Maheen Khurshid(74) *Attorney, Agent, or Firm* — Justin Lampel(57) **CLAIM**

The ornamental design for an atmosphere lamp, as shown and described.

DESCRIPTION

FIG. 1 is a perspective view of an atmosphere lamp showing the claimed design;

FIG. 2 is another perspective view thereof;

FIG. 3 is a top plan view thereof;

FIG. 4 is a rear elevational view thereof;

FIG. 5 is a left side view thereof;

FIG. 6 is a front elevational view thereof;

FIG. 7 is a right side view thereof; and,

FIG. 8 is a bottom plan view.

The broken lines depict portions of the atmosphere lamp that form no part of the claimed design.
